UNITED STATES PATENT OFFICE

JOSEPH SCHLAGHECK, OF TOLEDO, OHIO

DESIGN FOR A FISH-BOWL STANDARD

Application filed June 13, 1929. Serial No. 31,678. Term of patent 3½ years.

To all whom it may concern:

Be it known that I, JOSEPH SCHLAGHECK, a citizen of the United States, residing at Toledo, county of Lucas and State of Ohio, have invented a new, original, and ornamental Design for Fish-Bowl Standard, of which the following is a specification, reference being had to the accompanying drawing, forming part thereof.

showing my new design, the bowl being illustrated in dotted lines; and

Figure 2 is an edge view of the standard.

I claim:

The ornamental design for a fish bowl standard, as shown.

In testimony whereof I have hereunto signed my name to this specification.

JOSEPH SCHLAGHECK.
